UNITED STATES PATENT OFFICE.

CLAUDE L. WALLING, OF SHERBURNE, NEW YORK.

SNOWPLOW.

Application filed April 25, 1927. Serial No. 186,367.

My invention relates to improvements in snow or ice plows.

Snow or ice plows as ordinarily constructed, embody a blade or shear, disposed at a transverse angle to the direction of travel of the plow and is intended to work or throw snow or ice from the roadway to one side of the plow. The difficulty encountered in connection with this construction is that the snow sticks or accumulates upon the plow shear, to such an extent, that the proper or successful operation of the machine is prevented, if not entirely stopped. It is customary in machines of this character to scrape or remove accumulated snow from the blade by means of hand shovels or the like. Attempts have been made to automatically remove the accumulated snow from the plow blade or shear by means of rotatable fans or elements, arranged at the side of the blade. As far as I am aware, these fans have their blades so positioned that their longitudinal axes are radial with respect to the axis of rotation of the fan. These fans to be effective are rotated at a high speed, at about sixteen to eighteen hundred revolutions per minute. A machine equipped with this type of rotatable fan is open to the objection that when the plow is fed forwardly into the snow or ice, that such snow or ice offers such resistance to the rotation of the fan, that the fan is choked or stopped, or its rotation reduced below the point at which it is effective. In some instances, when these rapidly rotating fans are moved into a snow drift, the machine is fed rearwardly by the action of these fans upon the snow.

In accordance with my invention, I provide a snow plow embodying a transversely inclined blade or shear, which is fed forwardly into the snow, and a rotatable fan is located adjacent to the outer side of the blade, and functions to remove the accumulated snow from the blade. The fan is of a peculiar construction whereby it throws the snow from proximity to the blade, and will offer the least resistance with the snow, when fed forwardly into the same. This is accomplished by arranging the blades of the fan so that their longitudinal axes are substantially or generally parallel with the axis of rotation of the fan. As a result of this, the forward ends of the fans are initially brought into engagement with the snow, and these ends present the minimum area of

contact, with the consequent reduction in pressure between the snow and fan. The blades of the fan are, therefore, generally horizontally arranged, and in order that their longitudinal edges may not offer too much resistance by engagement with a snow bank or the like, at the side of the roadway, these horizontal blades are preferably equipped with spiral cutting blades, which will serve to shave or cut the snow bank.

Further, it has been found that the load placed upon the engine of a truck or automobile upon which the snow plow may be mounted is too great for the automobile engine, and I contemplate employing a separate engine to drive the rotatable fan or fans. The blades of my snow plow are angularly arranged and this provides a suitable space between them, for the reception of the forward end of the truck or the like, and also for the reception of the separate engine, and the gearing between this engine and the rotatable fans. This provides a very compact and advantageous arrangement, wherein the operating parts of the unit are out of the way.

In the accompanying drawings, forming a part of this specification, and in which like numerals are employed to designate like parts throughout the same,

Figure 1 is a plan view of a snow plow embodying my invention,

Figure 2 is a side elevation of the same,

Figure 3 is a front end elevation of the same,

Figure 4 is a rear end elevation of the same,

Figure 5 is a front end elevation of one of the rotatable fans or rotors,

Figure 6 is a longitudinal section taken on line 6-6 of Figure 5,

Figure 7 is a fragmentary plan view of one of the blades or shears showing an auxiliary guard above the fan or rotor, and,

Figure 8 is a plan view of a modified form of the invention.

In the drawings, wherein for the purpose of illustration, is shown a preferred embodiment of my invention, the numeral 10 designates an automobile, such as a truck, embodying chassis beams 11, hood 12 and front steering wheels 13. This is the usual automobile construction.

My snow plow embodies a lower scooping or raising blade or shear 14, the forward end 15 of which is suitably sharpened. This

scooping or raising blade may be constructed in any desired width, depending upon the width of the roadway which it is desired to clean, it being preferred that this blade extend for substantially the entire width of the surface to be cleaned. This scooping or raising blade 14 is slightly inclined and extends upwardly in a rearwardly direction, and by this arrangement only the forward end of the blade travels in contact with the roadway, thus reducing friction, and serving to vertically raise the snow or ice, thus tending to break up the same. The turning blade or shear 14 is provided with a longitudinal V-shaped opening 16, converging rearwardly, and the rear large end of this opening is adapted to receive the front end of the hood 12 and wheels 13, to afford sufficient space for the steering of the wheels.

The numeral 17 designates a yoke, extending over and above the hood 12 and bolted or rigidly attached to the front end of the chassis beams 11. This yoke is connected at its top and sides with rear diagonal braces 18, which extend rearwardly and downwardly and are bolted or rigidly attached to the chassis beams 11, as shown. Rigidly attached to the yoke 17 at its top and sides are forward diagonal braces 20, which are bolted or rigidly attached to upstanding turning blades or shears 21, as shown at 22. The rear ends of these turning blades are also connected with transverse diagonal braces 23, rigidly attached thereto, and to the top of the yoke 17. It is thus seen that a rigid truss structure is provided for mounting the rear end of the snow plow upon the forward end of the chassis of the truck. I have found that this connection is well suited for its purpose, yet the invention is not necessarily restricted to this precise connection, as other connecting means may be employed.

The upstanding turning blades or mold boards 21 are preferably formed of stiff sheet or plate metal, and these turning blades are angularly positioned with respect to each other, extend longitudinally above the blade 14, and converge forwardly. As a result of this, a triangular space is afforded between these turning blades or mold boards, which coincides with the space 16. At their lower edges, the turning blades 21 are riveted or otherwise rigidly attached to the scooping blade 14, and serve to stiffen and reinforce the same, attention being called to the fact that these turning blades extend for substantially the entire length to the generally horizontal scooping blade. These turning blades 21 are circularly curved in cross section with the curvature increasing rearwardly.

Riveted or otherwise rigidly attached to the rear ends of the turning blades 21 are preferably circular disks 24, upon the rear sides of which are rigidly secured diametrically extending bars 25, carrying V-shaped

brackets 26. The bars 25 are equipped with bearings 27 and the brackets 26 with bearings 28, and these bearings rotatably receive horizontal longitudinal fan shafts 29. The shafts 29 are equipped with collars 30', rigidly attached thereto, to prevent the rearward longitudinal displacement of the shafts. These shafts project forwardly beyond the disks or heads 24 into the turning blades 21 and are arranged above the scooping blade 14, and cleaning fans or rotors 30 are mounted upon these shafts, to turn therewith. Since these fans or rotors are identical, a description of one will suffice for both. Each fan or rotor embodies a rear disk 31, see more particularly Figures 5 and 6. This disk is rigidly mounted upon the shaft 29. Arranged in advance of the disk 31 and spaced therefrom is an auxiliary disk 32, of smaller diameter, which is also rigidly mounted upon the shaft 29. The numeral 33 designates blades, arranged in an annular series about the auxiliary disk 32, and engaging its periphery, and rigidly attached to the same by straps 34 or the like. The rear ends of these blades are also rigidly attached to the front face of the disk 31, by straps 35. The outer edges of the blades 33 are flush with the periphery of the disk 31. The blades 33 have their longitudinal axes arranged substantially horizontal and substantially parallel with the axis of rotation of the fan or rotor and its shaft 29. These blades have their transverse axes radially disposed with respect to the axis of rotation of the fan. The blades 33 are relatively long while they have a relatively short radial dimension. The forward ends of these blades are provided with short transverse heads 36, which are beveled or sharpened, as shown at 38. I preferably reinforce and connect the forward ends of the blades 33 by a ring 38', placed in notches 39 in the blades, and this ring is secured to the blades by straps 40 or the like. While the blades 33 are shown as horizontal, they may be slightly inclined, in which event they would preferably diverge rearwardly. However, the blades must remain generally horizontal, so that their ends, rather than their longitudinal edges will be brought into engagement with the snow or ice, during the forward feeding movement of the machine.

In order that the outer longitudinal edges of these blades may not improperly engage with a snow bank or the like along the roadway and thus offer excessive resistance against rotation, I equip these blades with spirally curved cutting blades or knives 41 rigidly attached to the outer longitudinal edges of the blades 33. These spiral cutting blades, therefore, initially engage with the snow and ice and cut or break the snow up before it is engaged by the blades 33.

In Figure 7, I have illustrated a hood or extension 42, which is hinged to the blade 16 at

43. This hood may be employed when it is desired to prevent the fans or rotors throwing the snow upwardly for too great an extent, as when cleaning a street or roadway in the front 6 of a dwelling. Where the machine is operating in the open country this guard is not necessary.

Referring more particularly to Figures 1, 2 and 4, it will be seen that the rear ends of the 10 fan shafts 29 have beveled gears 42', rigidly secured thereto, and these beveled gears engage beveled gears 43', rigidly mounted upon shafts 44, which are arranged within the space 16, and converge forwardly. The rear 15 ends of these shafts are held within bearings 45 while their forward ends are held within bearings 46, formed upon a brace-bracket 47, the ends of which are bolted or riveted to the turning blades or mold boards 21, and serve to 20 connect them and reinforce and stiffen the same. At their forward ends, these shafts 44 carry beveled gears 48, engaging a beveled gear 49, rigidly mounted upon a shaft 50, which may be the crank shaft of an internal 25 combustion engine 51, or a shaft suitably driven from such engine. The rear end of the shaft 50 is journaled in a bearing 52, carried by the brace-bracket 47. The engine 50 is rigidly mounted upon transverse bars 53, which 30 are rigidly attached to the turning blades 21, and serve to support the engine and to reinforce these blades. It is thus seen that a separate 35 motor is employed to drive the fan or rotors and that this motor is bodily mounted upon the blades 31 and is included in the snow plow unit. Further, the driving means between the motor and rotors or fans are also entirely mounted upon the snow plow unit. This is advantageous inasmuch as it permits 40 the snow plow unit being separated from the truck, when the snow plow is not in use and all parts of the snow plow will then be maintained intact.

In Figure 8, I have shown a plan view of a 45 modified form of the invention. In this figure the numeral 54 designates a scooping or raising blade or shear, corresponding generally to the blade 14. At the rear end of this blade 54 is a transversely inclined turning 50 blade 55, corresponding generally to one turning blade 21. A fan or rotor 56, identical with the fan or rotor 30, is mounted at one edge of the blade 54 upon the side of the turning blade 55. This fan is driven by a gear 57, engaging a gear 58, carried by a shaft 59. This shaft is 55 driven by a gear 60 engaging a gear 61, which may be driven from the crank shaft of the engine of the truck or automobile 62. When one rotor is employed, I have found that the same 60 may be driven from the engine of the truck but where two fans are employed, it is preferable to have a separate motor to drive them. Any suitable means may be employed to attach the rear end of the blade 54 with the 65 chassis of the truck, including bars 63 and 64.

In the operation of the first form of the invention, the engine 51 is set into action and drives the rotors or fans 30 in opposite directions, so that their upper portions are turning outwardly, as indicated by the arrows. These 70 rotors are preferably driven at about nine to fourteen hundred revolutions a minute, although the speed may be varied, as found advantageous, depending somewhat upon the character of the snow or ice to be handled. 75 The truck is now moved forwardly at a suitable speed, such as from about twelve to eighteen miles an hour, depending upon the conditions. The lower or elevating blade has its forward end scraping along the roadway and 80 will break or loosen up the snow or ice which feeds rearwardly upon the same to engage the turning blades or mold boards 21. Such snow or ice now travels in contact with the mold boards which tend to roll the same laterally 85 and outwardly whereby it engages the forward ends or blades 36 of the rotors. These rapidly rotating blades cut or break up the snow or ice before it enters the rotors. As the contact area of the ends of these blades is relatively small, the resistance that the snow or ice offers to the rotation of the rotors is slight. The major portion of this snow or ice enters 90 the rotors and is thrown outwardly by circumferential force as the same clears the top 95 edges of the turning blades 21. The discharge of the snow is also aided by radially and outwardly traveling currents of air, traveling in front of and behind the auxiliary disk 32. The air from behind the disk 32 is 100 supplied through the openings 31'. This air tends to aid in the discharge of the ice and snow and also clean the rotors. The longitudinal edges of the blades 30 are prevented 105 from initially contacting with banks of snow or ice along the side of the roadway, by the spirally curved cutters 41, which first shave or cut the same.

The operation of the form of the device shown in Figure 8 is very similar to that 110 stated in connection with the first form of the invention, the principal difference being that only one turning blade and rotor is employed.

It is to be understood that the forms of my 115 invention, herewith shown and described, are to be taken as preferred examples of the same, and that various changes in the shape, size and arrangement of parts may be resorted to without departing from the spirit of my invention, or the scope of the subjoined claims. 120

Having thus described my invention, I claim:—

1. In a snow plow, a scooping blade, a turning blade arranged above the scooping blade to deflect the snow or the like laterally and outwardly, a hollow rotor arranged near the outer side of the turning blade to discharge the snow or the like laterally and outwardly from the same, said hollow rotor embodying 125 spaced blades having their longitudinal axes 130

approximately parallel with the axis of rotation of the rotor, the forward end of the rotor being open so that the snow or the like may pass into the hollow rotor inwardly of said blades.

2. In a snow plow, a scooping blade, a turning blade arranged near and above the scooping blade to deflect the snow or the like laterally and outwardly, a hollow rotor arranged near the outer side of the turning blade and having its axis of rotation extending longitudinally of the scooping blade, said hollow rotor embodying spaced blades having their longitudinal axes approximately parallel with the axis of rotation of the rotor, said hollow rotor having its forward end open whereby snow or the like may pass into the same inwardly of the spaced blades, and means to drive the rotor.

20 3. In a snow plow, a scooping blade, a turning blade arranged near and above the scooping blade, a rotor arranged near the outer side of the turning blade and having its longitudinal axis extending longitudinally of the turning blade, said rotor embodying spaced blades having their longitudinal axes approximately parallel with the axis of rotation of the rotor, said blades being provided at their forward ends with cutting edges, the forward end of the rotor being open so that the snow or the like may enter the same, and means to drive the rotor.

4. In a snow plow, as a subcombination, a hollow rotor embodying an annular set of blades arranged at the periphery of the rotor and having their longitudinal axes approximately parallel with the axis of rotation of the rotor, said blades being provided at their forward ends with cutting edges, the forward end of the rotor being open so that snow or the like may pass into the hollow rotor inwardly of the blades.

5. In a snow plow, as a subcombination, a rotor embodying an annular set of blades having their longitudinal axes approximately parallel with the axis of rotation of the rotor, the forward end of the rotor being open, and spirally curved cutting blades arranged outwardly of the periphery of the rotor and connected therewith to turn with the same.

6. In a snow plow, a scooping blade, a pair of forwardly converging turning blades arranged near and above the scooping blade and extending laterally and outwardly, a pair of hollow rotors mounted outwardly

of and near the turning blades, said rotors having their axes of rotation extending longitudinally of the direction of travel of the snow plow, each rotor embodying spaced blades having their longitudinal axes approximately parallel with the longitudinal axis of rotation of the rotor, each rotor having its forward end open so that snow or the like may enter the same inwardly of the spaced blades, and means to drive said rotor.

7. In a snow plow, a scooping blade, a pair of forwardly converging turning blades arranged near and above the scooping blade and inclined laterally and outwardly, a pair of hollow rotors disposed near and outwardly of the turning blades, said rotors having their axes of rotation extending longitudinally of the direction of travel of the snow plow, said turning blades covering the inner portions of the rotors while their outer portions are uncovered, each hollow rotor embodying spaced blades having their longitudinal axes approximately parallel with the axis of rotation of the rotor, the forward end of each rotor being open whereby snow or the like may enter the rotor, and means to drive said rotor.

8. In a snow plow, a scooping blade, a pair of forwardly converging turning blades mounted upon the scooping blade and forming a space therebetween, rotor shafts arranged upon the outer sides of the turning blades and extending longitudinally thereof, rotors mounted upon said shafts, a motor mounted within the space between the turning blades, a pair of forwardly converging shafts arranged within said space, driving connecting means between the forward ends of the shafts and the motor, and driving connecting means between the rear ends of said shafts and the rotor shafts.

9. In a snow plow, a turning blade, means to move the turning blade forwardly in a longitudinal direction of the roadway, a rotor mounted to operate near the outer side of the turning blade, said rotor embodying spaced blades having their longitudinal axes approximately horizontal so that their forward ends initially engage with the snow as the plow is fed forwardly, the rotor being open at its forward end, and means to drive the rotor.

In testimony whereof I affix my signature.

CLAUDE L. WALLING.
